UNITED STATES PATENT OFFICE.

CONSTANTINE ALEXANDER HEGE, OF SALEM, NORTH CAROLINA, AS-SIGNOR TO C. A. HEGE & CO., OF SALEM, NORTH CAROLINA, A FIRM.

COFFEE-DRIER.

No. 841,964.

Specification of Letters Patent.

Patented Jan. 22, 1907.

Application filed April 27, 1898. Serial No. 679,029.

To all whom it may concern.

Be it known that I, CONSTANTINE ALEXANDER HEGE, a citizen of the United States, residing at Salem, in the county of Forsyth and State of North Carolina, have invented certain new and useful Improvements in Coffee-Driers; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to coffee-driers, and contemplates a machine devised especially for drying coffee.

In a machine for drying coffee it is necessary to provide against overheating the coffee-berries and to provide a construction that will approach as nearly as possible to the method of drying the coffee-berries by solar heat. To dry the berries, however, by the solar heat is a slow operation and dependent many times upon the condition of the weather. Having in mind the advantages of solar heat for drying of coffee, I have endeavored to devise a machine which will give as nearly as possible the results of solar-heat drying and at the same time render the operation more expeditious than by depending upon the solar heat and in which the operation can be carried on regardless of the condition of the weather, care being taken in devising the machine to provide against such a temperature of the heat employed as would tend to roast the coffee-berries, which, if permitted, would be disastrous, as is well known to all persons having to do with the raising and drying of coffee-berries.

With the above objects in view and to provide a simple and efficient machine for the purposes stated my invention consists in the construction and in the combination of parts arranged in relation to each other as herein-after particularly specified and then sought to be specifically defined by the claims, reference being had to the accompanying drawings, forming a part hereof, and in which—

Figure 1 is a perspective of the coffee-drying machine with a portion of the rotating cylinder and the top or cover broken away to

show the interior of the cylinder. Fig. 2 is a side elevation of the machine. Fig. 3 is an end view looking from the front end of the machine. Fig. 4 is an end view from the opposite end, showing a portion of the overhanging cover in section. Fig. 5 is a vertical longitudinal section through the machine. Fig. 6 is a vertical cross-section through the same, and Fig. 7 is a side elevation of the modified form of air-exhauster. Fig. 8 is a perspective of a testing-tube.

In the drawings the numeral 1 designates a casing made of suitable material and formed, preferably, of material or metal suitable for high temperature without danger of destruction by combustion. In the upper portion of this casing is mounted a cylinder 2, adapted to rotate, said cylinder having at least one, but preferably both, of its journals 3 made hollow. The walls of the cylinder may be perforate or imperforate, with the end walls or heads 4 thereof of reticulated material—for instance, of heavy wire-netting—said end walls or heads being secured to the ends of the cylinder by means of rims 5, which will clamp the wire-netting against the ends of the cylinder, as illustrated clearly in Figs. 1 and 5, the rims being held in place by rods 6, which extend longitudinally through the cylinder and lie quite close to the inner surface of the cylinder, so as to serve not only as the tie-rods, but also to assist in preventing the coffee from sliding uninterruptedly down the curved surface of the cylinder.

Within the rotating cylinder are secured any desired number of lifters 7, which may be supported therein in any suitable manner, although it is preferred to support the same upon rods 8, which will extend across the interior of the cylinder, the lifters being secured thereto by means of clip-bolts 9 or otherwise. These rods 8 are tubular and are secured in place by bolt-rods 10, which will extend through the tubular rods and the periphery of the cylinder and be held in place by means of nuts 11, formed on the threaded heads of the rods 10. The tubular rods 8 thus not only constitute a support for the lifters 7, but also serve to brace the cylinder by reason of their ends bearing against the inside face of the periphery of the cylinder. The lifters 7 are made L-shaped and applied in the man-

ner illustrated clearly in Fig. 6 of the drawings, so that in the rotation of the cylinder the lifters will not only serve to lift the coffee-berries on the ascending side of the cylinder, but will also to a greater or less extent serve to hold quite a body of the berries upon the lifters as the same rise with the rotation of the cylinder, and thus cause the berries to fall from the lifters gradually and in a comparatively small stream as the lifters ascend from the lower to the upper portion of the cylinder, the lifters continuing to retain and gradually discharge some of the coffee-berries until the lifters pass beyond the central line of the cylinder, as illustrated clearly in Fig. 6 of the drawings. By this construction and arrangement the coffee-berries are subjected in thin streams to the current of heated air drawn through the cylinder in the manner hereinafter specified and by reason whereof the berries are more thoroughly dried and the moisture carried off without injuring or impairing the qualities of the berries, either as to dryness or color.

25 Curved radial arms 12 extend from the rims 5 to the hubs 3 of the cylinder across the wire-netting 4, and on the periphery of one or both of the rims 5 are formed teeth 13, with which will mesh a pinion or pinions 14 on the ends of a shaft 15, said shaft outside of the casing 1 being provided with a wheel or pulley 16 for the application of power, either by a belt (not shown) passing around the wheel or pulley 14, although other means may be employed for driving the shaft and rotating the cylinder.

Within the casing 1, beneath the rotating cylinder 2, is placed a suitable heater 17 for heating the air in the casing 1 around the cylinder 2, so as to raise it to a temperature sufficient to dry the coffee-berries in the cylinder without liability of overheating or roasting the berries. If the products of combustion were permitted to come directly in contact with the walls of the cylinder 2, the heat would be too intense and the berries would be roasted or otherwise injured, and hence the necessity of heating the air in the casing 1 without permitting the products of combustion to come into direct contact with the drying-cylinder. If the casing 1 were open, the heated air would either escape and be wasted or else there would be difficulty in raising it to the best temperature for securing the best results in the drying of the coffee. If the cylinder 2 were stationary instead of rotatable, there would still be danger of overheating the cylinder, so as to injure the coffee, and if the coffee were permitted to slide down the sides of the cylinder without agitating it in its movement there would still be danger of overheating some of the berries and of not imparting sufficient heat to the others; but by having the chamber 1 closed and the heater 17 located therein below the

cylinder, as described, and by providing for rotation of the cylinder and the lifting of the berries in the rotation thereof by means of the rods 6 lying quite close to the surface of the cylinder and by reason of the lifters the several disadvantages enumerated are overcome, and a drier is produced in which all the berries are subjected to a uniform temperature alike, and the heat is so regulated as to thoroughly and expeditiously dry the coffee-berries without roasting or otherwise injuring the same.

75 While I do not restrict myself to any particular kind or type of heater to be located in the casing or shell below the rotating cylinder, still the type illustrated has been found very satisfactory for the purpose and may be of the type in which a fire may be built within the same, the heater in such case being provided with a door 18 for feeding the fuel thereto, the door having a damper 19 for regulating the draft, and the heater at the opposite end being provided with an exit-flue 20.

Instead of employing the heater 17, in which a fire is designed to be made or in connection therewith, I may employ a heater consisting of a steam-heating coil 21, which may extend beneath the rotating cylinder, the coils or pipes at one end being connected to the header 22 and at the other or forward end of the cylinder to another header 23, into which steam will be admitted from any suitable source through the inlet-pipe 24. These steam-pipes will enable radiated heat to be employed for drying the coffee, the same as has been described in reference to the fire heater or furnace 17.

For the purpose of creating a better circulation of the heated air through the rotating cylinder I locate said cylinder in its case so as to bring one end of the cylinder into contact with the inside face of one end of the outside case and so that the front end of the cylinder will set back a distance from the front end of the outside case, thereby forming a flue at the forward end of the machine between the end wall of the case and that end of the cylinder, as illustrated clearly in Fig. 5 of the drawings. This construction causes the heated air to pass from beneath the cylinder to the forward end of the machine and thence up through the duct or flue 24 and through the perforated end of the cylinder to the interior of the latter and thence through the cylinder to the opposite perforated head, from whence it will escape laden with such moisture as it takes up from the coffee-berries. The perforated or reticulated heads of the cylinder permit the free ingress of hot air and quick escape of the same with the moisture evolved from the berries during the drying operation, and hence the drying is rendered more expeditious than otherwise would be the case, and the most desirable results are thus obtained.

In order to facilitate and more effectually remove the moisture extracted from the coffee-berries, I form what for convenience I will designate an "exhaust-chamber" at one end of the case, which incloses the rotating cylinder. This chamber is designated by the numeral 25 and may be made by extending the upper part of the case or its cover so that it will project beyond that head of the rotating cylinder, as indicated in Fig. 5 of the drawings. For the purpose of creating a suction through this exhaust-chamber 25 I provide what is practically an ejector and which is designated by the numeral 26. This 10 ejector may be, as illustrated, a continuation of the smoke or exit flue, as illustrated in Fig. 5 of the drawings, this ejector opening into the exhaust-flue 27, which is just above and communicates with the exhaust-chamber 25. By this means I am enabled to create a strong current of air through the rotating cylinder, so as to quickly withdraw the air and moisture therefrom. For the purpose of regulating or controlling this exhaust 20 25 I provide a damper 28 in the exhaust-flue 27, this damper being of any suitable form and where it meets the ejector 26 being made to conform to the shape thereof, so as to fit closely to the same, as will be obvious by an 30 inspection of Fig. 5 of the drawings.

For the purpose of admitting fresh air to the inside of the casing 1 I provide openings 29 in one side of the casing, which openings are controlled by a slide-damper 30, working 35 in ways 31, said damper being formed with openings 32, corresponding to the openings 29 in the side of the casing. The damper is operated by a lever 33, and by adjusting the slide the openings therein may be brought 40 into register with the openings 29 in the casing, so that the air can pass therethrough into the interior of the casing. By adjustment of the slide-damper the size of the 45 openings may be regulated, and by moving the damper far enough the portions thereof between its openings may be brought opposite to the openings 29 in the casing, so as to entirely close the same. In this way the desired amount of air to be admitted can be 50 readily controlled. The air-inlets 29 in the side of the casing are located adjacent to the furnace or heater 17 and at a point below the center line of said furnace or heater, so that the air in entering will come into contact with the side of the heater, and thus be 55 warmed before it passes up and into contact with the rotating cylinder, which carries the coffee-berries.

The rotating cylinder 2 is provided in its periphery with an opening 34 for the insertion of the coffee-berries, said opening being provided with a slide-cover 35, which is secured in its closed position by means of a bolt and nut 36, a slot being made in the slide-cover 35, so that it may slide around the bolt

36 when its nut is loosened for the purpose of opening and closing the opening. In the wall of the rotating cylinder opposite the opening 34 are formed a number of openings 37, which are controlled by a damper 38, likewise 70 formed with a number of openings 39, which may be brought into register with the openings 37, so that when such is the case the coffee-berries, after they become sufficiently dried, may pass through said openings, and 75 thus out of the cylinder and into any suitable vessel or receptacle to receive the same. The slide-damper 38 is held in position by means of a bolt and nut 40, a slot 41 being formed in the wall of the cylinder 2 to permit adjustment of the slide-damper, so as to open or close the openings 37 in the wall thereof. In discharging the coffee from the cylinder the slide-door 35 may be open at the same time that the openings 37 are open, so that any 80 suitable implement may be passed through the opening 34 and manipulated so as to direct all the coffee-berries to the openings 37, through which they may be discharged. The lower side of the casing 1 at the bottom of the 85 casing may be formed or provided with the hinged door 42 to permit of the removal of the dried coffee-berries from the casing. The upper portion of the casing 1 is provided with a removable cover 43, which practically 90 forms a part of the walls of the casing 1 and which, preferably, is made to conform to the shape of the rotating cylinder, as illustrated, 95 said cover or upper portion of the casing being out of contact with the walls of the rotating cylinder, so as to leave a space between the cover and the cylinder for the circulation of hot air around the upper portion of the cylinder. The cover 43 or upper part of the casing is provided in its front end with a slide-door 44, which is provided with a thermometer 45 to indicate the temperature of the heated air around the rotating cylinder. I also provide thermometers 46 at appropriate 100 points in the side walls of the outside casing, so as to indicate the temperature of the air at 105 different points inside the casing and around the rotating cylinder. The cover or upper portion 43 of the casing is provided with a slide-door 47 to allow access to the interior of the casing, and by adjusting this slide-cover so as to leave uncovered a portion of the opening to which it is applied some of the heated 110 air may be allowed to escape if the temperature should rise above that which is desirable 115 for drying the coffee.

For the purpose of testing the coffee-berries in the cylinder 2 to ascertain if they have been sufficiently dried I employ a hollow sampling or testing tube 52, which is adapted 120 to pass through one of the hollow journals of the cylinder and to receive coffee-berries in the rotation of the cylinder, and in that way it can be accurately determined when the berries have been sufficiently dried.

In Fig. 7 of the drawings I illustrate a modified form of the air-exhauster, which connects with the interior of the rotating cylinder. In this form the numeral 48 designates a tapering or funnel-shaped exhaust-chamber, which at its inner end communicates with the interior of the rotating cylinder by being connected with the upper part of the case 1, or rather with its cover 43, as indicated in Fig. 7. 5
10 This tapering exhaust-chamber is flat on its under side and is formed with curved sides and top, which gives it the shape in cross-section of a section taken longitudinally through a funnel. The outer end of this exhaust-chamber communicates with a suitable fan 49, which may be supported upon a suitable stand 50 and be operated by means of a belt connecting with a pulley 51 or otherwise. This exhaust-chamber 48 will act in a similar manner to the exhaust-chamber 25, except that instead of using an ejector, such as the escape flue 20, as in Fig. 5, I use a fan 49, so as to exhaust the air from the interior of the cylinder as may be found necessary. In both forms 15 of this feature of the invention, however, it may be observed that there is used an exhaust-chamber and means connected therewith for the purpose of creating a regulated draft or exhaust through the same from the 20 rotating cylinder.

It may at this point also be observed that not only does heated air pass through the rotating cylinder, but also that the rotating cylinder is contained within the hot-air chamber, so that the heat is applied to both the inside and the outside of the cylinder, under which construction most satisfactory results have been found to exist in the drying of coffee-berries.

The machine described is simple in construction and inexpensive to build and meets all the requirements specified for the satisfactory and expeditious drying of coffee-berries without injury thereto. The temperature of the air in the shell or casing 1 can be easily regulated by controlling the heat generated in or evolved from the heater.

I have illustrated and described the construction which I have ascertained from actual operation of the machine to give most satisfactory results, and while the preferred details of construction are illustrated, still it is obvious that changes can be made in the various details without departing from the essential features of the invention.

Having described my invention and set forth its merits, what I claim is—
1. In a coffee-drier, the rotatable cylinder formed with perforations or apertures for the escape of moistened air and having within it longitudinally-extending lifting-bars located in proximity to the inner surface of the cylinder, in combination with a shell or casing for heated air, said cylinder lying partly above

and partly below the upper portion of said shell 65 and a closed heater lying below the rotating cylinder and inclosed within the lower portion of the chamber into which said rotating cylinder projects and adapted by radiation of heat from its walls to heat the air in the casing between said heater and rotating cylinder, substantially as described.

2. A coffee-drier comprising a shell or casing, a closed heater inclosed within the lower part of said shell, a rotatable apertured cylinder fitting in said casing or shell above the heater and lying partly above and partly below the upper portion of said shell, the lower portion of the cylinder projecting into the chamber occupied by the heater, a movable cover fitted to the casing or shell around the portion of the rotating cylinder lying above the shell and spaced from the latter, and a flue communication at one end between the chamber of the shell and the space between the cylinder and cover so as to permit heated air to pass from the casing or shell around the upper portion of the cylinder, substantially as described.

3. In a coffee-drier, the combination with 90 a shell or casing for heated air and a heater located in the lower portion of the shell or casing and adapted by heat radiating from its surface to heat the air in the casing or shell, of the rotatable cylinder fitting in said 95 casing or shell above the heater therein and composed of the cylindrical body, reticulated or apertured heads to said body, rims provided with teeth and having radiating arms fitting across the apertured or reticulated heads of the body, and tie-rods extending longitudinally through the cylindrical body and at their opposite ends secured to said rims so as to clamp the body, the arms and the heads together, substantially as and 105 for the purposes described.

4. A coffee-drier, comprising a shell or casing, a closed heater located in the lower part thereof, a rotatable apertured cylinder fitting in said casing or shell above the heater 110 and lying partly above and partly below the upper portion of the shell and formed with inlet and exit openings for the coffee-berries, said cylinder having one end close to one end of the shell and the opposite end set back 115 from the adjacent end of the shell to form a flue for the passage of heated air and a cover fitted to the casing or shell around the portion of the rotating cylinder above the casing and spaced from the cylinder so as to permit heated air to pass from the casing or shell to and around the upper portion of the cylinder substantially as and for the purposes described.

5. In a coffee-drier, the combination with a shell or casing, and a heater located in said shell or casing and adapted by radiation of heat from its surface to heat the air in said

shell or casing, of a rotatable cylinder fitting in said casing or shell, and lifters secured inside of the rotating cylinder, said lifters having portions extending laterally therefrom along their edges nearest the axis of the cylinder and in the direction of rotation of the cylinder and at a distance from the inner face of the cylinder so as to serve as a support for the berries and permit the latter to be gradually discharged therefrom in the rotation of the cylinder, substantially as and for the purposes described.

6. In a coffee-drier, the combination with a shell or casing, and a closed heater located in said shell or casing for heating the air therein, of a rotating cylinder in said casing formed with apertures for the escape of heated air and moisture therefrom, lifters secured inside of the rotating cylinder, said lifters having portions extending laterally therefrom along their edges nearest the axis of the cylinder and in the direction of rotation of the cylinder and at a distance from the inner face of the cylinder, an exhaust-chamber in communication with the shell or casing at one end of the rotating cylinder to facilitate the escape of heated air and moisture from the cylinder, and means for regulating the inflow of fresh air into the portion of the casing below the cylinder containing the heater, substantially as and for the purposes described.

7. In a coffee-drier, the combination of a shell or casing, a closed heater located therein for heating the air in the same, a rotating apertured cylinder in said casing or shell and lying partly within and partly above the portion of the casing containing the closed heater, an exhaust-chamber in communication with the shell or casing at one end of the rotating cylinder, an ejector in communication with said exhaust-chamber to increase the exhaust through the exit-chamber, and a removable cover constituting the top portion of the casing and spaced from the upper projecting portion of the cylinder, substantially as and for the purposes described.

8. In a coffee-drier, the combination of a shell or casing, a closed heater located therein to heat the air in the same, a rotating apertured cylinder within the shell or casing and lying partly within and partly above the portion of the casing containing the closed heater, an exhaust-chamber in communication with the shell or casing at one end of the rotating cylinder, an ejector for increasing the exhaust through the exhaust-chamber, a valve for regulating the exhaust therefrom, and a removable cover constituting the top portion of the casing and spaced from the upper projecting portion of the cylinder, substantially as and for the purposes described.

9. In a coffee-drier, the combination of a

shell or casing, a closed heater therein for heating the air in the same, a rotating apertured cylinder located in said shell or casing and lying partly within and partly above the portion of the casing containing the closed heater, an exhaust-chamber in communication with the shell or casing at one end of the rotating cylinder and having an exit-flue, a pipe leading from the heater in the lower part of the casing and in communication with the exit-chamber, and a removable cover constituting the top portion of the casing and spaced from the upper projecting portion of the cylinder, substantially as and for the purposes described.

10. In a coffee-drier, the combination of a shell or casing, a closed heater located therein for heating the air in the same, a rotating cylinder in the shell or casing formed with openings in its heads for the admission and escape of heated air, said cylinder having one end close to one end of the shell or casing and the opposite end set back from the adjacent end of the shell or casing to form a flue for the passage of the heated air from beneath the cylinder through said flue and into the cylinder, means at the opposite end of the cylinder for the escape of heated air and moisture from the cylinder, and means for regulating the inflow of fresh air into the portion of the casing below the cylinder, containing the heater, substantially as and for the purposes described.

11. A coffee-drier comprising a shell or casing, a closed heater located therein for heating the air in the same, a rotating cylinder inside the shell or casing having one end close to one end of the shell or casing and the opposite end set back from the adjacent end of the shell or casing to form a flue, an exhaust-chamber communicating with the shell or casing at one end of the rotating cylinder, means for increasing the exhaust through said exhaust-chamber, means for controlling the exhaust, and means for regulating the inflow of fresh air into the portion of the casing below the cylinder containing the heater, substantially as described.

12. In a coffee-drier, the combination of a shell or casing, a rotating cylinder located in said shell or casing, means for heating the air in the casing around the cylinder, means for conducting heated air from the casing to within the cylinder, means for regulating the exhaust of moistened air from the cylinder and also from the upper portion of the casing and means for exhausting the air through the cylinder, substantially as and for the purposes described.

13. In a coffee-drier, the combination of a shell or casing, a rotating apertured cylinder lying partly within and partly above a portion of the shell or casing, a removable cover constituting the top portion of the casing,

and spaced from the upper projecting portion of the cylinder, means for heating the air in the casing around the cylinder, and means for conducting heated air from the casing to within the cylinder so that heated air will be applied both inside and outside of the rotating cylinder, and means for regulating the inflow of fresh air into the portion of

the casing below the cylinder, substantially as and for the purposes described.

In testimony whereof I affix my signature in presence of two witnesses.

CONSTANTINE ALEXANDER HEGE.
